US00D840493S

(12) **United States Design Patent** (10) **Patent No.:** **US D840,493 S**
Bowman et al. (45) **Date of Patent:** **** Feb. 12, 2019**

(54) **COLLAPSIBLE PIN FOR FIREARM STOCKS**

(71) Applicants: **Michael Bowman**, Fullerton, CA (US);
George Ruiz, Hacienda Heights, CA (US)

(72) Inventors: **Michael Bowman**, Fullerton, CA (US);
George Ruiz, Hacienda Heights, CA (US)

(73) Assignee: **AIM Sports Inc.**, Ontario, CA (US)

(**) Term: **15 Years**

(21) Appl. No.: **29/596,768**

(22) Filed: **Mar. 10, 2017**

(51) LOC (11) Cl. **22-01**

(52) U.S. Cl. USPC **D22/108**

(57) **CLAIM**

The ornamental design for a collapsible pin for firearm stocks, as shown and described.

DESCRIPTION

FIG. 1 is a side view of a collapsible pin of the invention;
FIG. 2 is another side view thereof;
FIG. 3 is an enlarged top view thereof;
FIG. 4 is an enlarged bottom view thereof;
FIG. 5 is another side view thereof;
FIG. 6 is a view of the cross-section along the line 6-6 in
FIG. 5;
FIG. 7 is a perspective view of the pin in an upside-down
position; and,
FIG. 8 is a perspective view of the pin.

1 Claim, 8 Drawing Sheets
